UNITED STATES PATENT OFFICE.

ALSON C. SARGENT, OF DES MOINES, IOWA, ASSIGNOR TO SARGENT ELECTRICAL BRAKE COMPANY, OF DES MOINES, IOWA.

ELECTRIC MOTOR.

1,245,039.

Specification of Letters Patent. Patented Oct. 30, 1917.

Application filed March 6, 1916. Serial No. 82,463.

To all whom it may concern:

Be it known that I, ALSON C. SARGENT, a citizen of the United States, and resident of Des Moines, in the county of Polk and 5 State of Iowa, have invented a certain new and useful Electric Motor, of which the following is a specification.

The object of my invention is to provide an electric motor of simple, durable and 10 inexpensive construction.

A further object is to provide an electric motor of the rotary type having a stationary detachable switch with its parts arranged substantially in the same plane, and having 15 a brush, the switch having segments, the parts being so arranged that the motor is energized for movement depending upon the movement of the brush of the switch with relation to the segments.

20 A further object is to provide such a switch and brush with means for mounting the same in a convenient manner upon any suitable support, such for instance, as the steering post of an automobile, the parts being so arranged as to secure proper contacts regardless of vibration of the support.

25 A further object is to make such a device so arranged as to be peculiarly adapted for mounting it on a motor vehicle, with means for actuating a brush accessible to the driver of a machine.

30 My invention consists in the construction, arrangement and combination of the various 35 parts of the device, whereby the objects contemplated are attained, as hereinafter more fully set forth, pointed out in my claims and illustrated in the accompanying drawings, in which:

40 Figure 1 shows a plan view of a motor with the casing removed.

Fig. 2 shows a plan view of the switch.

Fig. 3 shows a side elevation of the switch illustrating the construction of the brush 45 and the manner in which the same is mounted on a steering post.

Fig. 4 shows a front elevation of the brush and a part of the switch.

Fig. 5 shows a side elevation of the motor for illustrating the mechanism for applying the motor to one particular use, namely, the controlling of the brake.

Fig. 6 shows an enlarged detail view,

partly in section of the motor and part of the mechanism shown in Fig. 5.

Fig. 7 shows a detail, sectional view of part of the mechanism shown in Figs. 5 and 6, and

Fig. 8 shows a detail, plan view of another mechanism for connecting the motor 60 with the brake rod.

In the accompanying drawings, I have used the reference numeral 10 to indicate a motor casing having a removable member 11. Extended through the casing is a motor shaft 12, on which is mounted a double-ended armature 13.

Arranged in a circle outside the path of travel of the armature and within the casing 10 are a plurality of field cores 27 to 70 36 inclusive. Any suitable number of field cores may be used, ten being shown in the illustration.

The cores are provided at their inner ends with portions 14, having elongated faces adjacent to the armature, so that room is left between the bodies of the cores for the wiring hereinafter mentioned and at the same time the inner faces of the cores project closer together than the bodies of the cores. 75 The advantage of such a construction lies partly in the convenience in winding, and the retention of air spaces or air insulation between the cores. There is another advantage which will be hereinafter referred to. 80 The ends of the armature 13 are elongated as shown in Fig. 1, so that each end is long enough to stand adjacent to and overlap the inner ends of two adjacent field cores, as 85 also illustrated in said figure. 90

It will be noted that the ends of the armature are formed with comparatively sharp edges 13^a for a purpose which will be hereinafter referred to. The cores are provided with separate wirings 15. 95

It is my purpose to provide a special form of switch especially adapted for controlling the motor and also to be mounted on a suitable support, such for instance, as the steering post of a motor vehicle.

In Fig. 3, I have shown a steering wheel 16 supported by a steering post 17 mounted within a steering post sleeve 18. The post 17 is hollow and received therein is a shaft 19, having at the upper end a suitable handle 20, whereby the shaft 19 may be rotated.

A quadrant 20^a is arranged to support and coat with the handle 20.

At the lower end of the shaft 19 is a suitable supporting member or frame 21, preferably constructed in such a way or of some material as to properly insulate the switch or controller members hereinafter described.

On the support 21 is a switch segment, 22, preferably made in a single piece, and 10 preferably comprising a strip forming the arc of a circle, of suitable conducting material.

Spaced from the switch segment 22 is a plurality of contact segments 23, of substantially the same size, preferably arranged in a 15 row in an arc of a circle, as shown in Fig. 2.

Suitably located is a source of electrical energy 24 connected by a wire 25 with the switch segments. A wire 26 connects the 20 source of energy 24 with the wiring of the cores 27 to 31 inclusive. The other end of the wiring of each of the cores mentioned, is connected with the wiring of the fifth removed core.

25 In Fig. 2, I have shown in diagrammatic form the wiring of the cores and have numbered the cores 27 to 36 inclusive, consecutively around the motor. Thus in further explanation of the wiring it may be said 30 that the wiring of each of the cores 27 to 36 inclusive is connected with the source of energy 24, and the opposite end of the wiring of each of said cores is connected with the wiring of the fifth removed core, the 35 wiring of the core 27 being connected with the wiring of the core 32, the wiring of the core 28 being connected with the wiring of the core 33, and so on. It will thus be seen that the wiring of each core is so connected 40 with the wiring of the opposite core that the cores are connected in opposite pairs and the members of each pair are wired to make them of opposite polarity. The other ends of the wiring of the cores 27 to 31 inclusive 45 are connected with the segments 23, as follows:

The first segment 23, at the lower right-hand side of the view shown in Fig. 2 is dead. The segment 22 is cut away at its 50 lower right-hand end, as shown in Fig. 2, opposite the first segment 23. The next two segments being the second and third segments, are connected by a wire 37 with the winding of the core 36, as shown in Fig. 2. 55 The wire 37 is also connected with the eighth segment, the thirteenth segment, the eighteenth segment, and so on. The wiring of the core 35 is connected by a wire 38 with the fourth segment, the ninth segment, the 60 fourteenth segment, and so on. The wiring of the core 34 is connected by a wire 39 with the fifth segment, the tenth segment, the fifteenth segment, and so on. The wiring of the core 33 is connected by a wire 40 65 with the sixth segment, the eleventh seg-

ment, the sixteenth segment, and so on. The wiring from the core 32 is connected by a wire 41 with the seventh segment, the twelfth segment, the seventeenth segment, and so on.

70 Fixed on the shaft 19 is a laterally extending arm 42, to the outer end of which is pivoted a brush holder arm 43.

Pivotal secured to the outer end of the brush holder arm 43 is a block of insulating material 44. Secured to the under surface of the block 44 is a brush 45 having at one end a downward extension 46 adapted to engage and travel on the segment 22. Pivoted to the other end of the brush 45 is a 80 brush member 47, which is long enough in the proper directions to extend across two of the segments 23 and the insulation between them. The outer end of the arm 43 is held in proper position for holding the 85 brush in contact with the segment 22 and the adjacent segments 23 by means of a spring 48 secured to the arm 42 and having a portion arranged to exert yielding downward pressure on the arm 43, as shown in 90 Fig. 3.

The segment 22 terminates at one end at such a point that when the brush member 47 is in contact with the first and second segments 23, the brush member 46 does 95 not contact with the segment 22.

When, however, the handle 20 is moved for rotating the shaft 19, for thereby moving the arms 42 and 43 in the direction indicated by the arrow in Fig. 2, until the brush member 47 reaches and contacts with the second and third segments, 23, then the extension 46 on the brush contacts with the segment 22. A current will be established through the segments 23, the wire 37, the 105 wiring of the core 36, the wiring of the core 31, the wire 26, the source of energy 24, the wire 25, the segment 22, and the brush. There will be, however, no tendency to move the armature 13, the ends of which will then 110 be opposite the cores 36 to 31.

A magnetic field will be established through the core 36, the inner end of which is north and through the core 31, the inner end of which is south. At the outer end of 115 the core 31 the magnetic field, as it were, divides and travels around the casing 10, as shown in Fig. 1, clockwise to 36. The other portion of the magnetic field travels anti-clockwise through the casing 10 to the 120 core 36.

When the brushes move a little farther, until the member 47 reaches the position in contact with the fourth segments 23, then the windings of the cores 36 and 35, and the 125 windings of the cores 31 and 30 will be included in the circuit, and a magnetic field will be established through the cores 36 and 35, and through one end of the armature and through a portion of the outer casing, 130

and another magnetic field will be established through the cores 31 and 30, and through the opposite end of the armature, and another portion of the casing 10, the 5 armature being moved from its position just above mentioned, to position where one end is opposite the cores 35 and 36, and the other end is opposite the cores 31 and 30.

When the brush is moved the width of another segment 23, a magnetic field will be established through the cores 35 and 34 and another magnetic field through the cores 30 and 29, thereby moving the armature one-tenth of a revolution. It will, of course, be 10 understood that the magnetic field includes the ends of the armature and the portions of the casing in each instance.

The movement of the brush is controlled by the handle 20 as desired, and when the 20 brush reaches position in contact with the thirteenth and fourteenth segments 23, the armature will have completed a full revolution.

It will be seen that the possible number 25 of revolutions of the armature in one direction before reversing its direction of movement is limited only by the number of segments 23.

It will be noted that there are times when 30 the ends of the armature are opposite three cores, because the brush contacts with three segments 23. For instance, the ends of the armature may be opposite the cores 35, 36 and 34, and opposite the cores 31, 30 and 29 in which case a magnetic field will be 35 established through the cores 35 and 36, another magnetic field through the cores 31 and 30; another magnetic field will be established through the cores 34 and 35 and another 40 magnetic field through the cores 30 and 29. This is an advantage in that it tends to give a more accurate and steady control of the armature.

When the handle 20 is moved for returning the arms 43 and 42 to their original positions, it will readily be seen that the direction of the rotation of the armature is reversed. When the brush reaches its position near the limit of its return movement where it contacts with the second and third segments 23, 50 it will be noted that after those segments have been connected together there is what might be called a magnetic field of longer duration for stopping and holding the armature, and preventing its movement past proper position by reason of its momentum acquired through the return movement of the brush. Substantially the same result might be accomplished by using a segment 55 of such length as to occupy, for instance, the space of the second and third segments shown. It will be noted that when the return movement is completed, the current is broken, so that there is no waste of electrical 60 energy when the device is not in use.

In Figs. 5, 6, and 7, I have shown a mechanism illustrating one of the many uses to which my motor may be put, namely the control of a band brake on a motor vehicle or the like.

In Fig. 8, I have shown a slightly modified form of said mechanism. In this connection it may be stated that there are a great variety of uses to which a motor of this kind may be put, and the mechanisms herein shown are simply for the purposes of illustrating such uses.

In Figs. 5, 6, and 7 I have shown on the motor shaft 12, outside the casing 10, a beveled gear 50.

Suitably mounted on the frame 51 of a motor vehicle is a bracket 52 which supports the motor casing and also supports a cylindrical casing 53.

Received within the casing 53 is a sleeve 54, on which is secured at one end of the casing 53 a beveled gear 55 in mesh with the gear 50. The sleeve 54 is internally screw-threaded. Extended through the gear 55 and received within the sleeve 54 is a screw-threaded shaft 56. On the sleeve 54 on the end thereof opposite the gear 55, is a collar 57. The collar 57 and the gear 55 prevent lengthwise movement of the sleeve 54 in the sleeve or casing 53.

Suitably mounted upon the frame 51 is a short rock shaft 57, to which is fixed a downwardly extending arm 58.

Pivoted to the lower end of the arm 58 is a sleeve 59, which slidably receives one end 100 of a rod 60. The other end of the rod 60 is pivoted to the shaft 56. The rod 60 has an enlarged portion 61 adjacent to the shaft 56.

Mounted on the rod 60 between the sleeve 59 and the enlarged portion 61 of said rod 105 is a coil spring 62 yieldingly tending to force the sleeve 59 away from the enlarged portion 61.

The sleeve 59 is provided with an elongated slot 63 in which travels a pin 64 which 110 extends outwardly from the rod 69, whereby the removal of the rod 60 from the sleeve 59 is prevented.

Fixed to the rock shaft 57 is an arm 65 to which is pivoted a brake-rod 66 for controlling a band brake 67.

Secured to the frame 65 and to the arm 51 is a spring 68 tending to act on the parts 65, 57, 58, and 59, for imposing some tension on the spring 62.

In the practical operation of the mechanism hereinbefore described, when the handle 20 is operated for moving the brush in the direction indicated by the arrow in Fig. 2, it will be seen that the movement of the armature rotates the shaft 12 and the gear 50 thereon. The gear 55 and the sleeve 54 are thus rotated whereby the screw-threaded shaft 56 is forced outwardly from the sleeve 54, thereby moving the arm 58 and 125 130

the parts operatively connected therewith against the tension of the spring 68 for setting the brake. By the interposition of the spring 62, I am enabled to secure with the mechanism herein shown, a more gradual application of the brake than could be otherwise had. By the manipulation of the handle 20 the brake may be applied as slowly or as rapidly as may be desired, and may be applied gently or may be locked as firmly as the operator may wish. By manipulation of the handle 20, in the opposite direction, the brake may be released as rapidly or as slowly as may be desired.

15 In Fig. 8, I have shown the brake-rod 66, the rock shaft 57, the arms 58 and 65, the parts 60, the sleeve 59, and the parts connected therewith which are similar to those already described.

20 In the form shown in Fig. 8, however, I have provided a worm 70 on the motor shaft in mesh with a worm gear 71 on the stub shaft 72.

Pivoted off center on the worm gear 71 is 25 a pitman rod 73 pivotally connected with the rod 60.

The operation of the mechanism shown in Fig. 8 is substantially the same as that shown in Fig. 6.

30 My improved motor has a large number of advantages some of which will now be referred to.

Attention is called in the first place to the use of the soft iron armature 13, employed 35 without any windings.

It is well known that the cost of wiring the armature in ordinary motors constitutes a very large part of the cost of wiring the motor, and by the construction herein 40 shown I have been enabled to materially reduce the expense of wiring the motor.

The form of the armature is believed to be novel and of importance, particularly in the arrangement of the elongated ends which 45 are of sufficient length to overlap two cores and are arranged with comparatively sharp edges. It will be noted that the body of the unwound armature comprises a comparatively thin bar or shank with each end terminating in a head of substantially the shape shown in Fig. 1, laterally elongated and having sharp side edges 13^a, said heads being inclined from such edges inwardly in the motor to said shank and being substantially 55 triangular in cross section.

The construction with the comparatively sharp edges, in connection with the construction of the ends 14 of the cores which also have comparatively sharp edges reduces to 60 a minimum the leakage of the magnetism between the armature and the adjacent cores not energized.

This construction of the ends of the armature and the inner ends of the core is also 65 such as to tend to cause the lines of greatest

magnetic force to travel through the central parts of the cores and armature ends. By the construction here shown I intensify the magnetic influence of the fields over the armature by centralizing the magnetic flux 70 in the body of the armature. By means of the form of head shown I provide paths for the flow of magnetism in as nearly straight lines as possible, which is obviously advantageous, at the same time drawing the lines 75 of magnetic force to a common path for centralizing the magnetic influence of the fields over the armature for the purpose of obtaining a much quicker and more positive action of the armature.

80 Attention is called to the advantage of the situation of wiring, whereby each connected pair of fields is connected with the segments 23 by a single lead wire with short branches whereby the amount of wiring is reduced to a minimum.

Another advantage of construction is found in the arrangement of the shaft 19, the handle 20 and the arms 42 and 43, whereby the device is peculiarly adapted for use 90 on a motor vehicle steering post.

Another advantage is found in the construction of the brush, whereby the brush supporting arm 43 is yieldingly held in contact with the segments 22 and 23 and of the 95 member 47 pivotally mounted on the brush, to make it possible to preserve such contact regardless of any vibration of the motor vehicle.

The construction herein shown permits accurate and absolute control at all times of 100 the speed of the armature and the extent of movement thereof.

By means of a single lever, I am able to control the speed, the extent of motion and 105 the direction of motion of the armature, it being possible by movement of the lever in one direction and by controlling the speed of movement of the lever to control the direction of movement and the speed of movement 110 of the armature, and by reversing the movement of the lever reverse the motion of the armature.

It will be seen that I have obviated the necessity for a second switch by using the controlling lever for reversing the movement 115 of the armature.

With such a mechanism as herein shown, it is possible, in the illustrative use herein described, to accurately control the speed 120 and the force of the application of the brake and the speed and force of the release thereof.

When the handle 20 is moved to a certain position for setting the brake and left in 125 such position, the brake may be set and held under any desired tension until the position of the lever 20 is changed.

The armature is a single piece of soft iron, unwound. With the ordinary wound 130

armature, in an ordinary motor having a plurality of stationary brushes, it is necessary to make the armature of the laminated type to break up the eddy currents. With my unwound armature, the creation of eddy currents is not so great and hence I use the single piece armature preferably cast *en bloc*, which greatly reduces the expense of building the motor.

- 10 I realize that changes may be made in the construction and arrangement of the parts of my improved motor without departing from its essential features and purposes, and it is my intention to cover by this application and the patent to be issued thereon any such changes which may be included within the scope of my claims.

I claim as my invention:

1. In a device of the class described, the combination of a vehicle frame with a switch thereon comprising a contact strip, a plurality of contact segments arranged in a line substantially parallel with said strip, a brush, means for yieldingly adjustably holding said brush in contact with said strip and segments, comprising a movable arm pivoted to swing on said frame, an arm member pivotally mounted thereon, a yielding device on said arm for engaging said arm member, a brush pivotally supported on said arm member, having a portion to contact with said strip, and a pivoted member to contact with said segments, whereby a combined triple pivotal brush and brush member support is afforded

2. In a device of the class described, a switch comprising a contact strip, a plurality of contact segments arranged in a line substantially parallel with said strip, an arm pivotally mounted to swing in a plane parallel with and spaced from the plane in which said switch lies, a pivoted member on

said arm, having its free end adapted to swing toward and away from said switch contact members, a brush mounted on the free end of said pivoted member, said brush having a member adapted to contact with said strip, and having a member pivoted to swing in a plane substantially at right-angles to the plane in which said pivoted arm member swings, and adapted to engage said segments.

3. In a device of the class described, a switch comprising a contact strip, a plurality of contact segments arranged in a line substantially parallel with said strip, an arm pivotally mounted to swing in a plane parallel with and spaced from the plane in which said switch lies, a pivoted member on said arm, having its free end adapted to swing toward and away from said switch, a brush pivotally mounted on said pivoted member having a contact member adapted to engage said strip, and having a member pivoted to swing in a plane at right-angles to said first planes, and adapted to engage said segments, and means for yieldingly pressing the opposite end of the pivoted member on said arm toward said switch.

4. In a device of the class described, a switch comprising a contact strip, a plurality of contact segments arranged in a line substantially parallel with said strip, a brush supporting arm adapted to be yieldably pressed toward said switch, a brush pivotally supported on said arm, having a member designed to contact with said strip, and having a member pivotally mounted to swing in a plane at right-angles to the plane in which the brush supporting arm has its yielding movement, adapted to engage said segments.

Des Moines, Iowa, February 29, 1916.
ALSON C. SARGENT.
